Primary Examiner — Michael A Maharajh

(57) **CLAIM**

The ornamental design for a beauty roller set, as shown and described.

DESCRIPTION

FIG. 1 is a front, top perspective view of a beauty roller set showing my new design;

FIG. 2 is a rear, bottom perspective view thereof;

FIG. 3 is a front elevation view of the handle and a roller of the beauty roller set;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another roller of the beauty roller set shown separately to show aspects of the design that are not visible when combined thereof; and,

FIG. 10 is the third roller of the beauty roller set shown separately to show aspects of the design that are not visible when combined thereof.

1 Claim, 8 Drawing Sheets
